(57) **CLAIM**

The ornamental design for a fishing magnet, as shown and described.

DESCRIPTION

FIG. 1 is a perspective view of a fishing magnet showing my new design;

FIG. 2 is another perspective view thereof;

FIG. 3 is a front elevational view thereof, the rear elevational view is identical;

FIG. 4 is a left side view thereof, the right side view is identical;

FIG. 5 is a top plan view thereof;

FIG. 6 is a bottom plan view thereof; and,

FIG. 7 is a partial enlarged view of FIG. 1.

The broken lines in the figures show boundaries of enlargements and form no part of the claimed design.

1 Claim, 7 Drawing Sheets(56)
